Patented Nov. 3, 1959

186,504

AUTOMOBILE VISOR ATTACHMENT FOR TOYS OR THE LIKE

Herbert S. Chase, Woodmere, N.Y., assignor to
Bernard Cahn Co., Inc., New York, N.Y.

Application February 13, 1959, Serial No. 54,605

Term of patent 14 years

(Cl. D14—6)

Fig. 1.

Fig. 2.

Fig. 3.

Figure 1 is a front perspective view of an automobile visor attachment for toys or the like, showing my new design.

Figure 2 is a rear elevational view, drawn to a smaller scale.

Figure 3 is a side elevational view thereof.

The essential features of my design reside in the portions shown in full lines in the drawing.

I claim:

The ornamental design for an automobile visor attachment for toys or the like, substantially as shown and described.
